FIG. 3

UNITED STATES PATENT OFFICE.

JOHN C. ROMAINE, OF SAN FRANCISCO, CALIFORNIA.

REFLECTOR.

1,330,009.

Specification of Letters Patent.

Patented Feb. 3, 1920.

Application filed July 7, 1919. Serial No. 309,067.

To all whom it may concern:

Be it known that I, JOHN C. ROMAINE, a citizen of the United States, residing at San Francisco, in the county of San Francisco and State of California, have invented new and useful Improvements in Reflectors, of which the following is a specification.

The object of the present invention is to provide a reflector, principally intended for incandescent electric lamps, which will greatly increase the light proceeding from the lamp, which will cause iridescent rays to be projected therefrom, and which will be cheap and simple in construction.

15 In the accompanying drawing, Figure 1 is a front view of the reflector, a lamp being shown in place relative thereto; Fig. 2 is a cross sectional view on the line 2—2 of Fig. 1; Fig. 3 is a plan view of a supporting plate 20 in its condition after being stamped and before parts are bent out of the plane of the plate.

25 Referring to the drawing, 1 indicates an incandescent electric lamp, here shown as extending downward. 2 indicates a sheet metal holder forming part of my reflector. It is formed with a central hole 3 sufficiently 30 large to be passed around the electric lamp 1, and from the edge of the plate around said hole extend, integral with the plate, apertured lugs 4, through the apertures in which screws 5 can be passed to secure the plate to the lamp socket 6. The outer portion of the plate is stamped to provide a 35 circumferentially extending series of slots 7, here shown as six in number, and a corresponding number of pairs of circumferentially extending tongues 8, outside said slots, said tongues 8 being connected to the main 40 portion of the plate by a narrow neck 9 between the slots.

45 11 indicates mirrors somewhat resembling hand mirrors of the usual form. Instead, however, of the ordinary handle, sufficiently long to be held conveniently in the hand, each mirror is provided with a short stub 12, the sides of which diverge outwardly from the mirror portion proper. Each mirror is of an oval shape, and its edge is 50 formed with scallops 13, said scallops being formed, however, not entirely through the glass of the mirror, but only in the front portion thereof, the face of each scallop making an angle of about 40° with the front surface 55 of the glass, so that the rear face of the glass

is of a continuous oval shape, while the front portion thereof is scalloped. These mirrors, of the same number as the slots and necks in the plate or holder, are secured to said plate by laying the stub of each mirror in contact 60 with one of said necks, and then bending the tongues 8 on opposite sides of said stubs over the stub. The sheet metal of the plate is sufficiently thick and strong to hold the mirror firmly in position, while it is not too 65 thick or strong to render it inconvenient to bend the tongues over the edges of the stubs.

70 By reason of the side edges of the stubs diverging outwardly from the mirror, it results that, when said tongues are bent over said edges and closely adjacent thereto, they prevent the stubs from being drawn outwardly in a radial direction from the plate. When said tongues are pressed down flat 75 upon the stubs, they hold the mirror firmly against movement in a direction at right angles to the plate.

70 By bending the necks along the line of juncture with the central portion of the plate, the mirrors can be arranged in planes 80 making any angle desired with the central portion of the plate. I have found that for a depending light, intended to throw a bright illumination onto a table or the like, an angle of about 20° is satisfactory. The rays of 85 light proceeding from the central lamp are then reflected by the mirrors so as to converge at a point at about the level of the table when the lamp is placed about a person's head when standing.

90 The reason for scalloping the edges of the mirrors is that, it produces an iridescent effect which is ornamental and attractive.

95 The simplicity and cheapness of the means for securing the mirrors in place will be noted. This means is made from a single piece of sheet metal stamped to the proper form, and its attachment to the electric lamp and to the mirrors requires no mechanism or tools, except screws and a screw driver.

100 I claim:—

1. A reflector comprising a circular series of radially extending mirrors spaced from each other and each having the spaced edges scalloped.

105 2. A reflector comprising a circular series of radially extending mirrors, the front portions only of said edges being scalloped.

3. A reflector comprising a sheet metal holder and a circular series of radially ex- 110

tending mirrors having at their inner ends stubs with diverging side edges, the holder having a corresponding number of pairs of tongues folded over the side edges of the 5 stubs.

4. A reflector comprising a sheet metal holder having a central round hole, and a

circumferentially extending series of radially extending mirrors having at their inner ends stubs with diverging side edges, the 10 holder having a corresponding number of pairs of tongues folded over the side edges of the stubs.

J. C. ROMAINE.
